No 124

John G. Moore. Design for spoon
Patented May 29, 1887.

Description.

Figs. 1 & 2. Observe the reverse side of the spoon.
 Letter a. fig 1. Shellat head of
 handle
 " b. Leaf of point, at the
 head of the stem C of
 the handle
 " C. Stem converging
 from a 6 pointed leaf
 at the bowl of the spoon
 and ending at the leaf b.
 " d. Bowl of the spoon.
 " e. 6 pointed work leaf.
 " f. 2 threads, (twisted) running
 the length of the stem C
 of the handle from the
 bowl to the leaf b.

Letter g. fig 2. Bowl of spoon.
 " h. Shell at shank of spoon
 " i. raised threads from h. & j.
 " j. leaf at end of the raised threads
 " k. leaf at head of the
 handle
 L. L. see obverse & reverse
 Eds. 2 raised threads
 around the neck or deep
 shaped head of the
 spoon, and ending in a
 general work supporting
 the leaves a. b. fig. 1 & k. of
 fig 2.

Des. 124

John C. Moore, New York, New York,
Xellers Patent, Design No 1241 dated 29th May 1877.

The schedule referred to, in these Xellers Patent and marking part of the same.

To all whom it may concern: Be it known that I, John C. Moore, of the City, County and State of New York, have invented & produced a new and ornamental design for embossing and beautifying the handles of spoons, Forks & Butter and fish knives, and do hereby declare that the following is a full and exact description of the same.

Figures 1 & 2. Obverse & reverse sides of a spoon. Letter a, of fig. 1, is a broken edged shell at the head of the handle, supported by 2 raised threads somewhat in a scroll shape. Letter b is a 5 pointed leaf at the neck of the violin shaped head of the spoon, resting on the stem c of the shank, and having on each side a raised thread scroll. Letter c the stem on which rests the leaf b, commencing at the point of the leaf, at the bowl of the spoon, and having 2 raised threads d, at either side of it, and on the upper ends of which rest the leaf b, and scroll threads at each side of the leaf b. Letter d, is the bowl of the spoon. Letter e, a 5 pointed leaf at the commencement of the bowl d, having its base divided into two stems or raised threads, which turning upward as side supporters to the stem c and at the leaf b in a scroll head. Letter f, 2 raised threads running from the bowl of the spoon to the leaf b, at which point, and in combination with the stem c, they terminate in a gradually swelling scroll head. Figure 2. letter g. reverse side of the spoon. Letter h, a raised shell like ornament covering the shank of the spoon, where the bowl joins the handle, and running into the threads i, of the handle, which support the leaf j, at the neck of violin shaped head of the spoon. Letter j, a small seven pointed leaf at the neck of the

2

Dec. 184

viol shaped head of the spoon, resting on the middle stem of the handle as shown at letter i, Letter k, a six pointed triangular leaf at the head of the spoon handle, surrounded by a thread somewhat like a scroll, and forming a projection on the broad end of the viol shaped head. Letters l, m, see figures 1 & 2, raised threads around the long sides of the viol shaped head of the spoon, and ending in the scroll work supporting the leaves a, b, figures a & j, k, figure 2.

Having now described the various devices and arrangement of the same for the purpose of ornamenting the handles of spoons, forks butter and fish knives, I will proceed to state what I claim and wish to secure by letters patent.

1st The particular device as shown in the drawings and explained above for ornamenting the obverse and reverse sides of spoons &c;

2nd The combination of the form of the handle with the ornaments and the particular arrangement of the devices.
